BOTTLE CLOSURE DISK.

Application filed July 30, 1925. Serial No. 47,092.

This invention relates to a closure commonly known as a "cap" or "stopper" of the circular disk type for milk bottles and analogous liquid containers in which the disk is of slightly greater diameter than the opening in the mouth of the bottle so that when forced into the opening it will be automatically held in place by frictional engagement of its periphery with the walls of said opening.

These disks are usually made of stiff paper or equivalent comparatively inexpensive material treated with paraffine or similar substance to render it impervious to moisture and the main object of the present invention is to provide a disk of this character with means whereby a peripheral portion thereof may be opened circumferentially or spirally in such manner as to permit the discharge of the liquid from the container through the opening without displacing the remaining portions of the closure from the mouth of the container and at the same time to allow the movable portion to be closed after each opening to protect the contents of the container from dust and other foreign matter.

One of the specific objects is to score the disk along inwardly convergent lines from the periphery in such manner that the intervening portion may be easily separated along one line from the main body and folded spirally and circumferentially along the other line to form a corresponding opening for the discharge of the liquid therethrough thereby forming what may be termed a relatively small supplemental closure which may be opened and closed at will without displacing the remaining portions of the closure from the mouth of the bottle.

Other objects and uses relating to specific parts of the device will be brought out in the following description.

In the drawings:

Figures 1 and 2 are top plans of a bottle closure embodying the various features of my invention with the movable section closed in Figure 1 and partially open in Figure 2.

Figure 3 is an edge view of the same closure.

Figure 4 is an inverted plan of the same disk.

Figures 5 and 6 are enlarged sectional

views taken respectively on lines B—B and A—A, Figure 1.

As illustrated, the closure consists of a comparatively thin circular disk —1— of paper card board or equivalent more or less laminated fibrous material of two or more ply coated or impregnated with paraffine or similar material to render it impervious to moisture, the diameter of the disk being slightly larger than the opening in the mouth of the bottle so that when forced into the opening it will be self-retaining by friction of its periphery with the walls of the opening.

The opposite faces of the disk are cut at —2— and —2'— along offset lines, preferably converging inwardly from the periphery toward the center of the disk, said cut lines being in this instance radial and at a slight angle to each other so that they may lie in more or less juxta-position but still in offset relation, the disk of each cut being equal to at least half and preferably slightly greater than half the thickness of the disk so as to form an intervening connecting web —3— in the plane of cleavage of the layers to permit the inner and outer halves of the web to be easily separated or pried apart by the finger nail or other implement adapted for that purpose.

The main body of the disk —1— is provided with a concave recess or depression —4— in its upper face extending laterally from the cut line —2— preferably near the outer end thereof to permit the entrance of the finger nail to the bottom of the cut line whereby the web —3— may be split along a medial plane thereby forming a radial division or slit from the center to the circumference of the disk and permitting the adjacent portion of said disk at one side of the slit to be sprung or turned upwardly in a spiral or circumferential direction as shown in Figure 2 and thereby to form an opening —5— through which the contents of the container may be discharged.

In order to facilitate this opening movement of the peripheral portion of the disk at one side of the slit, said disk is provided with an additional radial score —5— extending from the center to the circumference at an acute angle with the cut lines —2— and —2'— but at a greater angle than the angle between the first named cut lines thereby forming a supplemental closure sec-

tion —1'— which is integrally united to the main body along the score line —5— and is adapted to be deflected upwardly and circumferentially along the score line —5— 5 when the web —3— is split along a medial plane as previously explained to form the discharge opening —5'— extending inwardly from the periphery of the disk.

The score —5— extends only part way 10 through the thickness of the disk but is of sufficient depth to render the adjacent portion of the main body along said line flexible or bendable to facilitate the opening of the supplemental closure section —1— 15 when its opposite edge is detached from the main body.

It is, of course, understood that when the circular disk is pressed or forced into the opening in the mouth of the bottle or other 20 containers the supplemental closure section —1'— remains integrally united along the cut lines —2—, —2'— and —5— until it is desired to discharge the contents of the bottle at which time the finger nail may be inserted into the recess or depression —4— 25 and against the adjacent edge of the section —1'— with sufficient force to split the web —3— between the score lines —2— and —2'— thereby detaching the adjacent edge 30 of the section —1'— from the main body and permitting the entire section —1'— to be turned upwardly in a spiral or circumferential direction with reference to the circumference of the disk to form the opening —5'— 35 through which the contents of the container may be discharged.

If the contents are only partially discharged through said opening the remainder may be protected against the entrance of 40 dust or other foreign matter by simply closing the free edge of the section —1'— against the corresponding edge of the main body.

When the web —3— is split along a medial plane from one cut line —2— to the 45 other cut line —2'—, the free edge of the section —1'— and adjacent edge of the main body become rabbeted so that when a section —1'— is closed its free edge overlaps upon the adjacent edge of the main body, 50 the ledge —2''— at the rabbeted edge of the main body consists of a stop for limiting the inward movement of the free edge of the section —1'— and also cooperates with said

free edge to form a closer fitting joint than would be possible if the cut lines —2— and —2'— were in the same plane, it being understood that when the web —3— is slit in the manner described, the section —1'— may be opened and closed as often as may be desired with the assurance that when closed 60 it will protect the contents of the bottle against the entrance of external matter.

It will be observed that this disk including the cut lines —2— and —2'— and —5— and also the depression —4— may be formed 65 or stamped from the larger sheets in a single operation and that aside from the cut lines —2—, —2'— and —5— and depression —4— the opposite faces are smooth and parallel and that the entire disk is without 70 extra projections or other removing means and, therefore, the disks may be stacked flatwise one upon the other in compact relation and easily displaced one by one by any suitable mechanism when applying them to 75 bottles and that when applied to said bottles they form air and dust tight joints therewith and are impervious to moisture until it is desired to use the contents of the bottle at which time the seal at the web —3— 80 may be broken to permit the opening of the section —1'— when it is desired to discharge the whole or a part of the contents of the container.

What I claim is:

A bottle cap comprising a circular disk of paper board having opposite faces thereof cut along different radial lines from the center to the periphery of and substantially half way through the thickness of the disk at 85 a relatively small angle to each other, said disk being scored along a different radial line from the center to the periphery of the disk at a greater angle to both of the cut lines than the angle between said cut lines to 90 allow the portion of the disk between the cuts and score lines to be opened spirally from the periphery inwardly about said score line and thereby to form a triangular opening gradually diminishing in circumferential width from the periphery to the center of the disk.

In witness whereof I have hereunto set my hand this 27th day of July, 1925.

PHILIP G. FRANKLIN.
